UNITED STATES PATENT OFFICE.

HERBERT B. ROSE, OF BUFFALO, NEW YORK.

TOWEL-RACK.

No. 909,679.

Specification of Letters Patent.

Patented Jan. 12, 1909.

Application filed October 23, 1905. Serial No. 283,948.

To all whom it may concern:

Be it known that I, HERBERT B. ROSE, a citizen of the United States, residing at Buffalo, in the county of Erie and State of New York, have invented a certain new and useful Improvement in Towel-Racks, of which the following is a specification.

This invention relates to an improved support for towels or other articles of that class, which consists of a plate-like element adapted to be attached to a wall or the like and a supporting arm slidably mounted in an opening in said plate like element and adapted to be arranged in vertical non-supporting 15 position, or in horizontal supporting position.

The principal feature of the invention has reference to a ledge or shelf which is formed from the metal of the plate-like element and 20 extends beneath said plate-like element and serves to support the arm in substantially horizontal supporting position and also to direct the enlarged ends of the arm into their proper seat in the opening of the plate 25 like element.

The invention also relates to certain details of construction all of which will be fully and clearly hereinafter described and claimed, reference being had to the accompanying drawings, in which,—

Figure 1 is a top plan view of the improved support fastened to a wall and showing the arms arranged in horizontal supporting position. Fig. 2 is an enlarged front view of the improved support, showing the arms in horizontal supporting position. Fig. 3 is a view similar to Fig. 2, showing the arms in vertical non-supporting position. Fig. 4 is a section on line *a—a*, Fig. 2. Fig. 5 is a section on line *b—b*, Fig. 3. Fig. 6 is an enlarged top plan view of the improved support showing the arms in vertical non-supporting position. Fig. 7 is an enlarged bottom view of the improved support showing the arms in non-supporting position. Fig. 8 is an enlarged central longitudinal section through one of the arms showing the enlargement formed on one end only, before the arm is fitted to the plate.

50 In referring to the drawings in detail in which a preferred structure of the invention is illustrated like numerals designate like parts.

The plate-like element which in the pre-

ferred structure will be designated as the 55 supporting plate consists of a vertical member or part 1, which is provided with openings through which screws 2, or the like are inserted to fasten the plate to a suitable wall, and a substantially horizontal semicircular 60 member or part 3, extending outwardly from the lower end of the member 1, having its outer margin bent downward and outward to form a curved flange 4.

A series of circular openings 5, are cut in 65 the member 3, at regular intervals near the curved flange 4, and are so located that a line drawn through their centers will extend concentric with the curve of the flange. A slot 6, is cut to extend radially outward 70 from each of the openings 5, to and through the bend at the beginning of the flange 4, and through the flange to about the middle thereof. The strip of metal 7, which is cut partially from the plate to provide the slot 75 6, is bent to form a horizontal ledge or shelf extending inwardly from the lower termination of the slot, and located below and in a lower plane than the horizontal member 3. The flange is so bent that the edge of the 80 inner end of each of the ledges is vertically below the outer edge of the circular opening over it at the point where the slot commences and in fact completes the circular wall of the opening except that it is in a lower horizontal plane than the greater portion of the 85 wall.

The supporting arms or rods 8, are provided at each end with an enlarged ball 9, to prevent the detachment of the rods from 90 the plate, and these balls are preferably formed integral with the rods.

In assembling the device at the factory the supporting plate is first stamped and cut to the form heretofore described, the 95 rods 8, upon one end only of which balls 9, have been formed, are then operatively attached thereto by inserting their unenlarged ends into the circular openings 5, and finally balls are formed upon the said ends to lock 100 the rods to the supporting plate against detachment without interfering with the limited sliding movement necessary to change the arms from one position to another.

It should be noted that the balls are of 105 larger diameter than the circular openings so that it is impossible to entirely separate the arms from the plate when once they are

assembled. It will also be noted that the arms are smaller in diameter than the width of the slots so that the arms may slide easily in the slots.

- 5 The ledge or shelf not only serves to support the arms in a horizontal position but also to direct the enlarged ball ends to their seats in the circular openings and to strengthen and stiffen the supporting plate.
- 10 The chief advantage of the ledge however is that it is so located that it accurately centers each of the ball enlargements in the circular opening besides assisting to maintain and support the enlargement in said opening.

15 I claim as my invention.

1. In a device of the class described, a supporting plate having a flanged member provided with a series of openings and slots leading from the openings through a portion of the flange, horizontal ledges integral with the supporting plate, each of said ledges extending inwardly from the lower extremity of one of the slots and terminating vertically below the outer edge of one of said openings and a plurality of supporting arms slidably fitted through the openings in the flanged member of the plate and provided with enlarged ends larger in diameter than said openings; said arms being adapted to be supported when in a horizontal position by the ledges and to be directed into their proper seats in the openings by said ledges when sliding from an open position to a closed position, as set forth.

2. In a device of the class described, a supporting plate consisting of a vertical member adapted to be attached to a wall or the like, a substantially horizontal semi-circular member extending outwardly from the lower end of the vertical member and having its outer margin bent downward and

outward to form a curved flange; said horizontal member having a series of circular openings arranged in a curved line and also 45 being provided with a series of slots each extending radially outward from one of the openings and partially through the curved flange, integral horizontal ledges each extending inwardly from the lower end of one 50 of the slots and terminating vertically below the outer edge of one of the openings and a series of arms each of which is provided with a ball enlargement at each end slidably mounted in said openings, substantially as 55 set forth.

3. In a device of the class described a supporting plate having a curved flange and said plate being provided with a circular opening and a slot extending radially outward from said opening and partially through the flange, an arm slidably mounted in the opening and having enlarged ends and a ledge extending inwardly from the lower end of the slot and terminating vertically beneath the outer edge of the opening, substantially as set forth.

4. In a device of the class described, a plate-like element having an opening and a slot extending from said opening, an arm 70 slidably mounted in the opening and having enlarged ends and a ledge supported from the plate like element and extending inwardly from the lower end of the slot and beneath the slot; said ledge terminating beneath the opening and being adapted to direct the arm from one position to another and also to support said arm in horizontal position, substantially as set forth.

HERBERT B. ROSE.
